UNITED STATES PATENT OFFICE.

FRANK J. LE DUC, OF DETROIT, MICHIGAN, ASSIGNOR OF ONE-HALF TO
GEORGE C. WETHERBEE, OF SAME PLACE.

BRUSH-MAKING MACHINE.

SPECIFICATION forming part of Letters Patent No. 669,754, dated March 12, 1901.

Application filed June 25, 1900. Serial No. 21,547. (No model.)

To all whom it may concern:

Be it known that I, FRANK J. LE DUC, a citizen of the United States, residing at Detroit, county of Wayne, State of Michigan, have invented a certain new and useful Improvement 5 in Brush-Making Machines; and I declare the following to be a full, clear, and exact description of the invention, such as will enable others skilled in the art to which it appertains to make and use the same, reference being had to the accompanying drawings, which form a part of this specification.

My invention has for its object a brush-making machine of superior efficiency and 15 utility; and it consists of the construction, combination, and arrangement of devices hereinafter described and claimed, and illustrated in the accompanying drawings, in which—

20 Figure 1 is a front elevation. Fig. 2 is a side elevation. Fig. 3 is a view in horizontal section on the line 3 3, Fig. 1. Fig. 4 is a plan view. Fig. 5 is a view in section on the line 5 5, Fig. 2. Fig. 6 is a view in section 25 on the line 6 6, Figs. 1 and 7. Fig. 7 is a vertical section through portions of the device on the plane 7 7, Fig. 3, but showing features above the horizontal section on which Fig. 3 is taken. Fig. 8 is a view in vertical section 30 on the line 8 8, Fig. 4, showing portions of the staple-forming mechanism.

The object of my invention, more particularly, is to provide a machine for forcing a bunch or tuft of stock into a suitable socket 35 in a solid brush-head and to drive a staple thereover into the head to confine the stock in place. To this end my machine is intended to feed the stock under a reciprocatory driver, whereby the stock and staple are 40 driven into the brush-head, also means for feeding the wire from which the staples are formed, and mechanism to form the staples and feed them into position for driving into the head.

45 My invention also includes novel driving mechanism.

My invention, moreover, includes the general construction, arrangement, and operation of parts herewith disclosed.

50 I carry out my invention as follows: In the drawings, *a* denotes any suitable sup-

porting-frame, in which is journaled a driving-shaft *b*, provided with a pinion *c*, meshing with a gear *d* upon a shaft *e*. The driving-shaft *b* is shown provided with a driving-pulley *f*, belted by a belt *g* with any suitable source of power. A connecting-rod *h*, at one end thereof, is eccentrically connected with a disk *i* upon the shaft *e*. At its upper end said rod is connected with a lever *j*, fulcrumed 60 at its rear end upon a standard *k*. This lever *j*, as will be seen, is actuated by the connecting-rod *h*.

Upon the forward portion of the frame are located standards *l l*, preferably projecting 65 forward at their upper ends and converged, as shown in Figs. 1 and 2, their upper extremities being united by a cross-piece *m*. Intermediate their ends they are also united by an additional cross-piece *n*, which also projects forward of the standards *l l*, as indicated in Fig. 2. Through the cross-pieces *m* *n* reciprocates a plunger *p*, carrying a driving-spindle *q*. The plunger is constructed intermediate its ends with an elongated orifice, (indicated at *r*), into which the forward end of the lever *j* projects, the lever having a requisite free movement in engagement with said plunger owing to the forward end of the lever having an oscillatory movement. 70 The rod *h* may be connected with the lever *j* in any suitable manner, as by a yoke *s*. A table *t* is attached to the forward portion of the frame, provided with an orifice *u*, through which the driving-spindle may pass in its operation. The table is provided at the front and rear thereof with lateral guide-plates *w* *w* toward one extremity thereof to hold the ends of the stock in place, the front guide-plate being omitted in Fig. 1. 75

To assist the operation of feeding the stock into proper position and to hold the stock down properly upon the table, I also provide an upper guide or cover *x*, provided with an upwardly-curved projecting guide-arm *y*, to facilitate the introduction of the stock in place upon the table *t*, and with downwardly-projecting wings or flanges *v v*, having their lower edges spaced from the table, as shown, to permit a bunch of stock being engaged 80 thereunder.

Upon the table *t* is a reciprocatory pusher-

arm z to push the stock forward underneath the driving-spindle q . Over the pusher-arm z is a plate, (indicated at the numeral 8,) having its forward end turned downward and bifurcated, as indicated in Figs. 6 and 7, to form a guide-opening at 9 and having downwardly-projecting arms or prongs 1 and 2, Fig. 6, on either side of said opening, through which opening the reciprocatory arm z may pass. A cover plate 10 is also provided, located over a portion of the plate 8. It will be perceived that forward of the plate 8 is thus formed a stock-receiver space or opening between the forward end of said plate 15 and the guide-arm y , (indicated at the letter o , Figs. 1 and 7,) into which opening a bunch of stock may be placed by an attendant and forward of the retracted end of the pusher-arm z . The table t , it will be understood, 20 is stationary and the stock is placed upon an immovable portion of the machine, the pusher-arm z pushing the stock into place on the immovable table under the driving-spindle q . The attendant may not only place the 25 bunch of stock in the opening o , but may also without difficulty or hindrance force the bunch of stock under the wings or flanges $v v$.

I do not limit myself solely to any particular mechanism for actuating the reciprocating pusher-arm z , but, as shown in the drawings, a lever 11 is provided, fulcrumed to the frame, as indicated at 12, the forward end of the lever 11 being properly connected with the arm z , as indicated at 13.

Engaged upon the lever j is a yoke 14, said yoke provided with arms 15 and 16, projecting downward on each side of said lever. With the arm 16 is pivotally connected a cam-plate 17, as shown at 18, said cam-plate bearing 20 against the rear end of the lever 11 to actuate said lever, and thereby actuate the pusher-arm z .

A staple-runway is indicated at 19. To form the staple, the wire (indicated at 20) is fed over the rear arm of the runway. A suitable plunger 22, carried by the lever j , forms the staple upon its descending movement, said plunger cutting the wire at the same time of proper length to form the staple. To 25 force the staples off from the arm 21 when formed, I provide a bell-crank lever 23, provided with forwardly-projecting arms 24, connected with the lower end thereof, as indicated at 25. Said lever 23 is fulcrumed upon 30 a bracket 26, as indicated at 27. To actuate the lever 23, the connecting-rod h is provided with an arm 29, constructed with a beveled projection (indicated at 30) underneath the upper end of the lever 23. It will readily be 35 seen that as the beveled projection 30 contacts with the upper end of the lever 23 in the upward movement of the rod h the bell-crank 23 will be actuated to force the staples off from the horizontal portion of the runway, the staples thereby descending into position under the driving-spindle q , the staples being received upon one end of a spring-arm 31. Upon

the descent of the driver the staples will be forced off from the extremity of the spring-arm and into place in the brush-head.

To the arm 15 of the yoke 14 is rigidly connected a cam-plate 28. The cam-plate 17 has a movement similar to that of the connecting-rod h —viz., a vertical movement and a laterally-oscillatory movement.

To feed the wire, the supporting-frame a is provided with a bracket or table 32. Upon a slide 37 is carried a standard 33, provided with a dog 34, fulcrumed thereto, provided with downwardly-projecting arms 35 and 36 to 80 grip the wire. This slide 37 is actuated by a lever 38, fulcrumed to the frame, as indicated at 39, said lever being actuated by the cam-plate 28. The slide 37 reciprocates in a guide-plate 39^a. Said guide-plate and the table 85 32 are provided with upwardly-projecting flanges 40 and 41, through which the wire is fed, a weight 42 engaging the wire, preferably between said flanges, as shown in Figs. 1 and 5. The lever 38 is provided adjacent to the 90 arm 36 of the dog with a beveled face, as indicated at 43. It will be perceived that as the lever 38 advances toward the dog the arm 35 of the dog will thus be tilted downward to grip the wire to feed the wire forward. The 95 return movement of the lever 38 releases the dog from gripping the wire, the wire being held from retracting by the weight 42 as the slide carrying the dog recedes.

To govern the movement of the wire so as to 100 regulate the size of the staple desired, the lever 38 may be provided with a gage-arm 43^a, which may be adjusted toward or from the cam-plate 28. A guide-arm 44 may also be employed through which the wire is passed.

At one side of the opening u is a stop 45, the stop being located on the side of the opening opposite the pusher-bar and serving to hold the bunch of stock from being pushed too far, the stop confining the bunch of stock 110 in proper position under the driving-spindle as the pusher-arm advances, forcing the stop into position. A portion of the framework, as indicated at 46, is also carried forward under the driving-spindle and provided with 115 an orifice, as indicated at 47, through which the staple passes to engage astride a bunch of stock forced into position thereunder.

To hold the staple in position, the orifices u and 47 are provided with marginal recesses, as indicated, for example, at 48 and 49. Underneath the table t is a shoulder 50, provided with an orifice 51 therethrough, through which the stock and staple are carried to the socket in the brush-head. This orifice of the shoulder 50 is also provided with recesses 48 and 49. The stop 45 is provided with one of the grooves, as indicated at 49, while the forward end of the pusher-arm is formed with a corresponding groove 48. When the pusher-arm 125 z is advanced to carry the bunch of stock into position, said arm remains up in forward position until the staple passes between it and the stop 45, so as to assist in guiding the sta-

ple as it is forced downward. After the staple passes the end of the pusher-arm said arm is then retracted, affording opportunity for feeding an additional bunch of stock into the opening *o*. By having the pusher-arm remain up in advanced position before returning until the bunch of stock forced forward thereof is forced downward with the staple astride thereof it assists materially in guiding the staple to the work. When the pusher-arm recedes, it remains in retracted position for an ample time to feed a bunch of stock into the opening *o*.

A customary support or table (indicated at 15 52) is employed, upon which the brush-head is located, beneath the driving-spindle. This support or table 52 may be arranged and constructed in any suitable manner. I prefer to connect the rear extremities of the levers 11 20 and 38 by a spring (indicated at 53) to retract said levers. It will be perceived that all of the working parts of the machine are actuated from the connecting-rod *h*. The cam 17 is preferably connected to the rod *h* by a bar 25 54 to give to the cam the motion of the connecting-rod *h*. A stop 55 is also provided to limit the retraction of the push-bar *z*. The lever 11 is preferably connected to the push-bar by an intervening link 56, or otherwise, 30 as may be desired.

The operation of the machine will now be understood. The machine being in motion, a bunch of stock is fed by the attendant into the opening *o* and may be forced by the attendant under the wings or flanges *v v* of the cover *z*. The pusher-arm then advances, forcing the bunch of stock firmly against the stop 45 and under the wings *v v* between the openings *u* and 47. While the pusher-arm 35 is in advanced position, as above described, the driving-spindle descends, forcing a staple through the opening 47 astride the bunch of stock, and as the driving-spindle further descends the bunch of stock, with the staple, 40 is forced downward through the opening *u* and through the opening in the shoulder 50, the bunch of stock being thereby folded. A brush-head upon the table 52, having a socket suitably adjusted under the shoulder 50, receives 45 the bunch of stock forced downward by the driving-spindle, the spindle driving the staple into the brush-head. While the driving-spindle is descending to accomplish this result the lever 38 is being actuated to 50 advance the wire and the plunger 22 is descending to cut off the wire of proper length and form the staple. As the lever *h* ascends the bell-crank 23 is actuated to force the staple upon the forward end of the runway 19, 55 and the various parts which are advanced by the downward stroke of the lever *h* recede into retracted position, giving opportunity to feed another bunch of stock into the opening *o*. The plunger 22 is bifurcated at its lower 60 end, and the wire 20 is fed across the rear arm of the runway 19. As the plunger de-

scends the end of the wire is cut off for a sufficient length to form the staple, and the two ends of the severed piece of wire are bent downward over the rear arm of the runway. 70

It is evident that the forward end of the plate 8 separates the stock-receiver from the retracted forward end of the pusher-bar.

What I claim as my invention is—

1. In a brush-making machine, the combination with a support, of a staple-driving device, a stationary table upon which a bunch of brush-stock may be placed, means to supply staples to the brush-stock under the driving device, a pusher-bar reciprocatory upon 80 said table to push the brush-stock into place under the driving device, a plate located over the pusher-bar having its forward end projecting downward, and bifurcated for the passage of the pusher-arm therethrough. 85

2. In a brush-making machine, the combination with a support, of a staple-driving device, a stationary table upon which a bunch of the brush-stock may be placed, means of supplying staples to the brush-stock under 90 the driving device, a reciprocatory push-bar to push the brush-stock into place under the driving device, lateral guides to hold the ends of the stock in place, and a cover constructed with downwardly-projecting wings, and with 95 an upwardly-projecting guide-arm, a plate located over the pusher-bar having its forward end turned downward and bifurcated for the passage of the pusher-arm therethrough, said upwardly-projecting guide-arm of the 100 cover spaced from the forward bifurcated end of the plate located over the pusher-bar forming an opening therebetween for the introduction of a bunch of brush-stock upon the stationary table in front of the pusher-bar. 105

3. In a brush-making machine, the combination with a support, of a staple-driving device, a stationary table constructed with a grooved aperture, a grooved stop at one side of said aperture, a reciprocatory pusher-bar 110 grooved at its forward end, and means to supply staples to the stock under the driving device.

4. In a brush-making machine, the combination with a support, of a staple-driving device, a stationary table constructed with a grooved aperture, a grooved stop at one side of said aperture, a reciprocatory pusher-arm 115 grooved at its forward end, and means to supply staples to the stock under the driving 120 device, the pusher-arm arranged to remain in advanced position when the staple is forced downward past its forward end.

5. In a brush-making machine, the combination with a support, of a reciprocatory 125 slide, a wire-feeding dog fulcrumed upon said slide formed with downwardly-projecting arms, and a lever to actuate said slide, said lever arranged to tilt the forward arm of the dog downward as the lever is advanced, and to release the dog as the lever is retracted. 130

6. In a brush-making machine, the combination with a support, of a reciprocatory slide, a wire-feeding dog constructed with downwardly-projecting arms at its extremities and fulcrumed upon said slide, means to tilt downward the forward arm of the dog as the slide advances, and means to hold the wire from receding when the slide is retracted.
- 10 7. In a brush-making machine, the combination with a support, of a reciprocatory driving device, a lever to actuate said device, and an eccentrically-actuated connecting-rod to actuate said lever, a staple-runway, staple-forming mechanism, and means actuated by said connecting-rod to force the staple upon the runway into position under the driving device.
- 15 8. In a brush-making machine, the combination with a support, of wire-feeding mechanism, staple-forming mechanism, a staple-feeding device, a staple-driving device, a lever to actuate the driving device, an eccentrically-actuated connecting-rod to actuate 25 said lever, feeding mechanism to feed a bunch of brush-stock into position under the driving device, a lever to actuate the staple-forming mechanism, and a lever to actuate the mechanism to feed the stock, a yoke engaged with said connecting-rod, and cam-plates connected with said yoke to actuate the wire-feeding mechanism and the brush-stock-feeding mechanism.
- 30 9. In a brush-making machine, the combination with a support, of staple-forming mechanism, a bell-crank lever to feed the staples
- 35 to the work, a beveled arm to actuate said lever, and means to actuate said arm.
10. In a brush-making machine, the combination with a support, of a staple-driving device, 40 a lever to actuate the driving device, an eccentrically-actuated connecting-rod to actuate said lever, wire-feeding mechanism, a lever to actuate the wire-feeding mechanism, mechanism to feed a bunch of brush-stock to 45 the work, a lever to actuate the stock-feeding mechanism, and cam-plates actuated by said connecting-rod to actuate the levers operating the wire-feeding mechanism, and stock-feeding mechanism, one of said cam- 50 plates having a vertical movement, and the other of said cam-plates having a vertical and an oscillatory movement corresponding to the movement of the connecting-rod.
11. In a brush-making machine, the combination with a support, of a staple-driving mechanism, a stationary table constructed with an aperture through which a suitable driving device reciprocates, a stop at one side of said aperture, a reciprocatory pusher-bar 60 forming, in its advanced position, the opposite side of said aperture, and means to supply staples to the stock under the driving device, the pusher-bar remaining in advanced position until the driving device has moved 65 downward therewith to the work.
- In testimony whereof I sign this specification in the presence of two witnesses.
- FRANK J. LE DUC.
